Primary Examiner—M. N. Pandozzi**CLAIM**

The ornamental design for the non-spill party plate, as shown and described.

DESCRIPTION

FIG. 1 is a perspective view of the non-spill party plate showing my new design;

FIG. 2 is a front elevational view thereof;

FIG. 3 is a rear elevational view thereof;

FIG. 4 is a left side elevational view thereof, the broken line showing of the cup for illustrative purposes only and forms no part of the claimed design;

FIG. 5 is a right side elevational view thereof;

FIG. 6 is a top plan view thereof;

FIG. 7 is a bottom plan view thereof; and,

FIG. 8 is cross-sectional view thereof taken along line 8—8 of FIG. 2.
